UNITED STATES PATENT OFFICE

2,339,825

DRYING CELLULAR ORGANIC PRODUCTS

Benjamin R. Warner, Evanston, Ill., assignor to
The Guardite Corporation

Application May 28, 1942, Serial No. 444,909

4 Claims. (Cl. 34—15)

This invention relates to a method of drying cellular organic products and more particularly to a method of controlling the drying of such products in an atmosphere of steam at pressures below atmospheric in such a way as to produce the maximum rate of drying and to produce a product which rehydrates with the maximum speed and effectiveness.

The invention has particular reference to processes such as those described in the copending application of applicant and John M. Baer, Serial No. 428,506.

In this connection I have discovered the very surprising fact that the more rapidly a given product is dehydrated under a predetermined set of conditions, without altering its physical state, the more rapidly and efficiently it reabsorbs water, and the farther its drying can be carried without destroying its ability to rehydrate.

Ability to rehydrate may be reduced or destroyed by a great variety of factors, some of which are known and some of which are not. For example, it is well known that products can be dried to such an extent that they will not readily pick up water, and in some cases will reacquire it only with extreme difficulty, if at all. Sometimes this change is due to a profound chemical alteration in the product. In other cases it appears to be due merely to a collapse or clogging of the capillaries.

It is obvious of course that under any given set of conditions the rate of drying may be increased by raising the available heat input, but, if this is carried on too far, the ability of the material to rehydrate may readily be destroyed by scorching or burning. It is, therefore, important not to dry at too great a rate, and for the reasons already given, it is essential to dry at as rapid a rate as is possible.

I have discovered that the rate of drying may be mathematically determined for any given material, apparatus, and source of heat, and thereafter the process may be regulated in accordance with such determination. Control is effected according to the following formula:

$$\frac{dw}{dt} = k_1 \Delta p e^{-k_2 w/w_0}$$

where

$\frac{dw}{dt}$ = rate of water removal.

Δp = the difference in vapor pressure between the vapor pressure of water at the temperature of the product and the vapor pressure of water in the surrounding atmosphere.

w = the weight of water which has been removed from the product.

w_0 = the weight of original water content of the product.

5 e = the natural logarithm base.

k_1 and k_2 are constants.

The constants k_1 and k_2 may be determined from the experimental data contained in any trial runs. They must be determined of course for any given apparatus. The constants are relatively close for various types of materials if the state of subdivision is substantially the same and the initial water content is substantially the same. The formula may be substantially simplified and the need for the determination of the constants eliminated if desired by plotting $\log p$ against w . It may be shown mathematically that when the resulting curve is a straight line,

$$\frac{dw}{dt}$$

is a maximum, so that the maximum rate may readily be determined by mere observation of Δp and weight of water removed plus an arithmetical operation. When using only radiation as a source of heat the water removed may be measured by condensation.

When using superheated steam as a means of supplying some of the energy required, w is difficult to measure. It has been found, however, that plotting the product of Δp and time against Δp gives a straight line when

$$\frac{dw}{dt}$$

35 is a maximum.

It appears that when the product is dried at less than the maximum rate, the cell walls and particularly the capillaries may shrink to such a point that rehydration will not occur, whereas the use of the maximum rate of drying keeps the cell walls and capillaries from contracting to a point in the drying far beyond that possible at slower rates.

45 A break in the curve

$$\log \frac{1}{\Delta p} \frac{dw}{dt}$$

against

$$\frac{w}{w_0}$$

50 toward the end of the drying indicates a basic change in the structure of the product, which changes the diffusion constant k_2 . Drying at the maximum rate substantially delays this break in

the curve so that it is possible to dry the product to a greater degree without altering its basic structure.

The control has been found suitable on drying vegetables, such as carrots, beans, potatoes and sweet potatoes, and meat products of various types. The products preferably are dried in small particles.

The temperature of the product may be obtained by the insertion of thermocouples within it. In making this determination it is advisable to employ a considerable number of thermocouples and use the average thereof as the temperature of the product.

The form of apparatus or the exact type of drying is not part of this invention. Any suitable vacuum chamber may be employed and various heating means may be utilized. Preferably the heat energy necessary is supplied predominantly by radiant heat but this is in the preferred form supplemented by the use of superheated steam. It is highly desirable that substantially all air be eliminated from the system. If it is not eliminated, the determination of Δp is extremely difficult.

It is obvious that the particular units employed in measuring the various factors above described are unimportant. This is particularly true in determining the maximum rate of drying inasmuch as the selection of units merely changes the slope of the curve, and the slope is generally unimportant. In some cases it is desirable to select units which will give a curve having a slope in the neighborhood of 45° rather than one which is either close to 0° or close to 90° .

The equation given in claims 1 and 2 may be solved by application of well-known mathematical and engineering principles to a test run.

The table below gives the data of a test run in which the product was $\frac{1}{2}$ " cubes of diced meat which had been precooked. The weight of the meat was 1800 grams and the original weight of water content (w_0) was 1040 grams. The operating pressure was 57 m. m.

This equation may then be put into the form

$$\log_e \frac{1}{p} \frac{dw}{dp} = \log_e k_1 - k_2 w/w_0$$

5 by taking the log of each side of the equation. The

$$\log_e -k_2 \frac{w}{w_0}$$

10 is minus

$$k_2 \frac{w}{w_0}$$

15 It is obvious that the curve represented by the above equation is a straight line. Furthermore, the slope of the curve is k_2 since the equation is of the form $y = b + mx$. In an equation of the form $y = b + mx$, m is the slope of the curve and in the above equation k_2 is the equivalent to the m in the form equation.

20 Similarly $\log_e k_1$ equals the y intercept since if

$$\frac{w}{w_0}$$

25 equals zero, the $\log_e k_1$ represents the only value on the right hand side of the equation.

Figure 1 in the drawing hereof shows the plotting of the aforesaid curve from which it is obvious that k_2 is approximately 7.7 and k_1 is approximately 33.2.

Furthermore, since the values lie within experimental error of a straight line the drying is being conducted at the proper rate.

30 In carrying out the above work, any suitable form of drying apparatus may be used and the instruments required are simply thermometers, pressure gages and scales. The weight of the water removed may be measured by condensing the steam in the exhaust and measuring the amount of super heated steam supplied to the system. An apparatus suitable for performing the operation is illustrated in the co-pending application of applicant and John M. Baer 428,506, filed January 28, 1942.

In applying the results of this table in order to calculate k_1 and k_2 the formula is first reduced to a form in which these may most readily be calculated. This may be done by dividing both sides of the equation by p which gives the following equation:

$$\frac{1}{p} \frac{dw}{dp} = k_1 e^{-k_2 w/w_0}$$

70 The same form of apparatus and the same type of measurements may be employed in making the calculations called for in the other claims. In fact, the formula given in claims 3 and 4 is a simplified method of calculating the same results shown by claims 1 and 2.

The foregoing detailed description has been 75 given for clearness of understanding only, and no

unnecessary limitations should be understood therefrom.

What I claim as new, and desire to secure by Letters Patent, is:

1. The method of drying a cellular organic product naturally containing a substantial quantity of water which comprises regulating the rate of drying in accordance with the formula

$$\frac{dw}{dt} = k_1 \Delta p e^{-k_2 w/w_0}$$

where

$\frac{dw}{dt}$ =rate of water removal,

Δp =the difference in vapor pressure between the vapor pressure of water at the temperature of the product and the vapor pressure of water in the surrounding atmosphere,

w =the weight of water which has been removed from the product,

w_0 =the weight of original water content of the product,

e =the natural logarithm base,

k_1 and k_2 are constants.

2. The method of drying a cellular organic product naturally containing a substantial quantity of water which comprises regulating the rate of drying in accordance with the formula

$$\frac{dw}{dt} = k_1 \Delta p e^{-k_2 w/w_0}$$

where

$\frac{dw}{dt}$ =rate of water removal,

Δp =the difference in vapor pressure between the vapor pressure of water at the temperature of the product and the vapor pressure of water in the surrounding atmosphere,

5 w =the weight of water which has been removed from the product,

w_0 =the weight of original water content of the product,

e =the natural logarithm base,

10 k_1 and k_2 are constants,

to produce substantially complete drying without a significant change in the structure of the product.

15 3. The method of drying cellular organic water-containing material which comprises regulating the rate of drying to produce a straight line curve when plotting $\Delta p T$ against Δp , where Δp represents the difference between the vapor pressure of water at the temperature of the product and the vapor pressure of water in the atmosphere surrounding the product, and T equals the time of treatment.

20 4. The method of drying cellular organic water-containing material which comprises controlling the rate of drying to produce a straight line curve in plotting the $\log \Delta p$ against w , where Δp =the difference in vapor pressure between the vapor pressure of water at the temperature of the product and the vapor pressure of water in the surrounding atmosphere, and w =the weight of water which has been removed from the product.

BENJAMIN R. WARNER.

Certificate of Correction

Patent No. 2,339,825.

January 25, 1944

BENJAMIN R. WARNER

It is hereby certified that errors appear in the printed specification of the above numbered patent requiring correction as follows: Page 1, first column, line 50, in the equation, for

$$\frac{dw}{d} \text{ read } \frac{dw}{dt}$$

page 2, in the table, sixth column from the left, fifth line from bottom, for "0.831" read 0.850; and that the said Letters Patent should be read with these corrections therein that the same may conform to the record of the case in the Patent Office.

Signed and sealed this 14th day of March, A. D. 1944.

[SEAL]

LESLIE FRAZER,
Acting Commissioner of Patents.
